[57] CLAIM

The ornamental design for a fishing reel clutch lever, as shown and described.

DESCRIPTION

FIG. 1 is a front elevational view of a fishing reel clutch lever showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a vertical sectional view thereof taken about line 6—6 of FIG. 7;

FIG. 7 is a vertical sectional view thereof taken about line 7—7 of FIG. 5; and

FIG. 8 is a perspective view thereof as an element of a reel.

The reel in FIG. 8 has been shown in broken lines for illustrative purposes only and forms no part of the claimed design.
